UNITED STATES PATENT OFFICE.

LOUIS L. KROUPA, OF CHICAGO, ILLINOIS.

ELECTRIC SWITCH.

Application filed December 8, 1923. Serial No. 679,286.

My invention relates to improvements in electric switches, and has for its main object the provision of an improved device of this character especially adapted for use in 5 circuit testers, with which a plurality of circuits may be separately and readily tested, to detect blown out fuses and poor connections and breaks, which interfere with the proper flow of current through the conductors.

Other objects will appear hereinafter.

The invention consists in the combinations and arrangements of parts hereinafter described and claimed.

15 The invention will be best understood by reference to the accompanying drawings forming a part of this specification, and in which

Fig. 1 shows a switch embodying my invention as applied to a circuit box or fuse box, and being connected with the branch circuit terminals in said box;

Fig. 2 is an enlarged central section taken longitudinally through the switch;

25 Fig. 3 is a view of the switch with the cover plate and dial plate removed;

Fig. 4 is a sectional view taken on line 4—4 of Fig. 2, and

Fig. 5 is a diagrammatic view of the 30 switch in conjunction with the circuit box.

In the drawings I have shown my invention applied to a circuit box or fuse box 10 containing a plurality of pairs of branch circuit terminals 11 and 11' to which the 35 usual branch circuit wires (not shown) are connected in a well-known manner; each pair of terminals being connected to the main feed members 12 and 13, and cartridge fuses 14 and plug fuses 15 are interposed in 40 said connections, said pairs being consecutively numbered, as shown in Fig. 1.

The preferred form of construction of my 45 tester comprises supporting means including a casing 16 having openings for bolts or members 17 for fastening the casing to the circuit box, and an insulating member 18, preferably in the form of a disk with a central opening, which disk is mounted in said casing with brackets 19 and suitable fastening members. Contact members including metallic plates 20 and 20', are arranged in pairs which are suitably spaced around said disk, and the members of each pair being placed one on the forward and the other on 55 the rear face of said disk; while yoke-shaped, resilient contact elements 21 and 21' are

mounted with arms in slots at the front of said plates 20 and 20' and are curved over to form jaws 22 and 22' which extend inwardly into the central space in said disk. Conductors 23 and 23' are connected to said plates 20 and 20' by the use of suitable flanged washers and binding posts 24 and 24', as best shown in Fig. 2, said conductors extending through one of the sleeves or nipples 25 provided on the casing, to the terminals 11 and 11' of the fuse box.

The movable switch means includes an arm 26, of insulating material, which is rotatably mounted with necks 26' in a pair of metallic conductor strips 27 and 27', by the use of a shaft 28 and collars 29 and 29' fastened on said arm 26. A pair of contact blades 30 and 30' are fastened on said arm 26 and engage with conductor strips 27 and 27', at the necks 26', and said strips being arranged to engage between the jaws 22 and 22' of any one of said pairs of stationary contact means, sufficient space being allowed between succeeding pairs of jaws to permit free movement of said blades from one pair to the next and so as to prevent cross sparking during such movement. A pin 31 is mounted in a slot in arm 26, at the end opposite blades 30, and is urged outward by a

75 spring 32 to engage in notches 33 in the disk 18 for guiding and holding the contact blades 30 and 30' in correct position within jaws 22 and 22'.

A standard or any other suitable socket 34, carrying a light 35, is mounted in a slot 36 in disk 18, and a flexible conductor 37 leads from said socket to contact strip 27, said conductor 37 and strip 27' being connected through terminal screws 38 and 38' to the light 35, in the usual manner; and said strips 27 and 27', light 35, members 38 and 38' and said flexible conductor 37 providing a complete conductor between the blades 30 and 30' on said arm 26. A normally open switch 39, preferably of the push button type, is interposed in said flexible conductor 37, and opens automatically when the testing is completed and the button is released, in order to prevent waste of current by acts of careless persons. A suitable knob 40, disposed outside of casing 16, is provided with an angular sleeve 41 which engages collar 29 for rotating the switch arm 26 to test the fuses and branch circuits.

110 Means is provided for indicating the particular branch circuit with its pair of fuses

which is being tested, said means comprising a dial 42, which is preferably of metal with numbers 43 appropriately stamped thereon, said numbers being visible, with the light 35, 5 through a slot 44 in the removable top plate 45 of the casing 16, by turning knob 40. Appropriate numbers, to correspond with said dial numbers, are placed adjacent the branch line terminals 11 and 11', between each pair 10 of fuses 14 and 15, in the fuse box, as shown in Fig. 1; and corresponding numbers are also placed on contact plates 20, as shown in Fig. 3, to assure accurate connecting of the terminals 11 and 11' with the corresponding 15 binding posts 24 and 24', by means of conductors 23 and 23'.

It is apparent from the above disclosure that with a tester constructed as disclosed the conductors 23 and 23' can be accurately 20 connected with the terminals 11 and 11' marked number "1" on the dial, as shown in Fig. 1, and with the corresponding binding posts 24 and 24' on the disk 18, which are likewise marked number "1" as shown in Fig. 25 3; and that by pressing the button for closing the button switch 39 and by turning the knob 40 until number "1" on the dial plate appears under slot 44, the connections will be completed to illuminate light 35 if there 30 are no defects and the current flows properly through the conductors, and if the light fails to shine that the fuse 14 is blown out or the light is defective. The release of the button will open switch 39 and prevent the waste of 35 current even if the knob 40 has not been turned to inoperative or off position. It is also apparent from the disclosure that the contact jaws and conductor blades in the tester may be used in a single series, although 40 they have been shown arranged in pairs comprising each pair a front set 22 and 30 and a rear set 22' and 30' of jaws and blades respectively, and disposed in double series; and it is apparent that either set may be 45 omitted or cut out, for instance, by separat-

ing the conductor strip 27' from blade 30' and connecting said strip with a suitable conductor directly to the member 13 of the main feed members, and that the tester will thus properly function with only the other set of 50 blades and jaws in action.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 55 the appended claim.

Having described my invention, what I claim as new and desire to secure by Letters Patent is:

A switch comprising a casing, a stationary 65 supporting plate in said casing and being of insulating material in the form of a disk having its center removed; a plurality of pairs of contacts on opposite sides of said plate, the members of each pair being arranged directly opposite each other; a plate of insulating material rotatably mounted in the central opening of said supporting plate; a spring held pin in said rotatable plate adapted to engage notches in said supporting plate; a pair of contacts on opposite sides of said rotatable plate to connect simultaneously with the members of the pairs of contacts on said supporting plate; a plurality of circuits, each circuit having its ends 70 connected with a pair of contacts on said supporting plate; a sight opening in said casing; a signal light in said casing, viewable through said opening; and controlled by said switch, and a handle member on said switch 75 outside of said casing for operating said switch.

In testimony whereof I have signed my name to this specification.

LOUIS L. KROUPA.
